UNITED STATES PATENT OFFICE.

ERNEST G. CLARK, OF DE KALB, ILLINOIS, ASSIGNOR TO THE Q R S MUSIC COMPANY,
OF CHICAGO, ILLINOIS, A CORPORATION OF ILLINOIS.

HAND STAMPING DEVICE.

1,337,591.

Specification of Letters Patent. Patented Apr. 20, 1920.

Application filed July 30, 1919. Serial No. 314,392.

To all whom it may concern:

Be it known that I, ERNEST G. CLARK, a citizen of the United States, residing at De Kalb, in the county of Dekalb and State of Illinois, have invented certain new and useful Improvements in Hand Stamping Devices, of which the following is a specification, reference being had to the accompanying drawings, forming a part thereof.

10 The purpose of this invention is to provide an improved device for applying markings by a printing stamp adapted for rapid operation and accurate placing of the markings and uniform distribution of the ink on the stamp and consequent uniformity throughout the area of the mark so applied. It consists in the elements and features of construction shown and described, as indicated in the claims.

20 In the drawings:

Figure 1 is a plan view of a device embodying this invention.

Fig. 2 is a side elevation of the same.

Fig. 3 is an inverted plan view of the stamp holder.

Fig. 4 is a detail section at the line, 4—4, on Fig. 1.

In the structure shown in the drawings, 1 is a bed in which is contained at 2 an inkpad 30 and at 3 a platen for the sheet to be marked. 4, 4, are fulcrum supports secured to the opposite side edges of the bed midway in its length and projecting upward past the upper surface of the bed to afford journal 35 bearings for a rock shaft side, which with its two arms, 6, 6, constitutes a radius member for carrying the stamp holder, 7, which is pivoted between the ends of the arms, 6, 6, on said radius member. The stamp holder

40 may be adapted in any desired manner for carrying on its under face the stamping or printing means, such as rubber stamps, assembled types, electrotype blocks or stereotype plates or the like. It has dove-tail 45 grooves, 7^b, 7^b, adapted to receive the mounting blocks, 8 and 9, of stamping or printing devices which may be understood to be either electrotype, stereotype or rubber printing plates mounted upon a backing

50 block, as seen at 10 in Fig. 4. At 11 there are shown metal retainers of the general character of turn buttons or latches held in place on the holder, 7, by a single screw, 12, on which the turn button or latch may turn

for engaging or releasing the stamping or printing device from the holder. At the right hand side of the stamp holder, 7, there is secured upon its back or upper surface a check bar, 13, whose ends extend beyond the side edges of the stamp holder and overhang 60 the radius arms, 6, 6, when the radius member is brought over to the left to carry the stamp to the platen, 3; and through these overhanging ends, 13^a, of said bar, 13, there are set adjustable stop screws, 14, 14, which 65 collide with stop plates or wear plates, 15, 15, mounted on the radius arms at the sides thereof which are upward when the radius member is swung over as described, onto the platen, but which are downward when it 70 stands at the position shown in full lines in Fig. 1, with the stamp resting on the ink pad. The stop screws, 14, are to be adjusted so that they will collide with the radius arms, 6, 6, when the printing face is in a 75 plane distant from the axis of the rock shaft as far as the plane of the platen (or of the sheet lodged thereon for printing) is distant from said axis, so that the printing face will come to the platen squarely,—that 80 is, so as to make contact therewith over the entire printing surface, and thereby produce an evenly inked impression upon the sheet lodged on the platen for receiving the imprint. 17, 17 are screw eyes set into the 85 edges of the printing blocks, 8 and 9, for convenience of withdrawing them from their seats in the holder. 18, 18, are turn-buttons for securing the printing block. 20 is a handle for engagement by the operator to 90 swing the stamp holder back and forth between the ink pad and the platen.

I claim:—

1. A device for the purpose indicated, comprising in combination with a radius member pivoted for swinging through an arc for carrying a printing stamp from an inking pad to a printing position, a printing stamp holder pivoted at the free end of said radius member, said member and said holder having coöperating stops positioned for coming into collision at the printing limit of said swing.

2. In a structure defined in claim 1, a bed; an inking pad and a platen for lodgment of 105 a sheet to be printed, both the pad and the platen being contained on the bed, and fulcrum supports to and between which the

radius member is pivoted for swinging to carry the stamp holder either to the pad or to the platen.

3. In a structure defined in claim 1, the radius member being a rock shaft having radius arms near its opposite ends, and fulcrum supports between which said rock shaft extends and in which its ends are journaled.

10 4. In a structure defined in claim 1, the stamp holder having a bar secured on its upper or back side whose ends extend beyond the sides of the holder to overhang the radius member arms, said bar carrying in 15 its said ends stops on the holder for colliding with the radius member stops.

5. In a structure defined in claim 1, the radius member being a rock shaft having two arms, the holder being pivoted to and 20 between said arms, and having a bar on its

upper side whose ends project beyond the holder to overhang said rock shaft arms respectively, the holder stops being mounted in said overhanging ends.

6. In a structure defined in claim 1, the radius member being a rock shaft having two arms, the holder being pivoted to and between said arms and having a bar on its upper side whose ends project beyond the holder to overhang said rock shaft arms respectively, the holder stop consisting of screws set through said overhanging ends and adapted to be screwed therethrough to vary their protrusion and consequent encounter with the stops of the radius arms respectively.

In testimony whereof I have hereunto set my hand at De Kalb, Illinois, this 21st day of July, 1919.

ERNEST G. CLARK.
